SHEET METAL TABLE HAVING HOLLOW END PANELS SUPPORTING THE TABLE TOP

Harvey G. Knuth, Elgin, Ill., assignor to Lyon Metal Products, Incorporated, Aurora, Ill., a corporation of Illinois

Filed Sept. 4, 1958, Ser. No. 759,032

7 Claims. (Cl. 311—110)

This invention relates to a sheet metal office table and more particularly to a table having hollow end panels supporting the table top.

Contemporary sheet metal tables, particularly of the type having hollow supporting end panels, have not been entirely satisfactory chiefly because of their expense; the difficulties and expense of assembling and disassembling the supports, particularly hollow end panels, to the table top and the excessive lateral flexibility of the hollow end panels.

It is accordingly an object of this invention to provide a sheet metal table of materially reduced cost but superior quality and improved rigidity and which is capable of such simple and rapid assembly and disassembly without tools of any kind as to eliminate any need for factory assembly of the table or shipping or moving the table in assembled form.

Another object of the invention is to provide a table having hollow, top supporting end panels, and panel securing means fixed to and projecting from the end side of the table top and so constructed as to be readily telescoped into the end panels and upon being telescoped to automatically and properly locate, and relatively align, the end panels and also rigidify the panels and secure the same in rigid relation to the table top.

A still further object of the invention is to provide a table of the contemporary hollow end type so constructed that the two end panels may be quickly and effectively secured against detachment and in rigid relation to the table top by a minimum number of fastening elements and without use of tools.

These and other objects and advantages of the invention will be apparent from the following description when taken in conjunction with the accompanying drawings wherein:

Figure 1 is a view in perspective of, and from below, a table embodying the invention;

Figure 2 is an enlarged fragmentary view in perspective, and partially in section, of the top of the table in Figure 1 and showing the structure of an end panel locating and rigidifying bracket;

Figure 3 is an enlarged fragmentary view in vertical section taken along the line 3—3 of Figure 1;

Figure 4 is a fragmentary view in vertical section taken along the line 4—4 of Figure 3; and

Figure 5 is a fragmentary view in horizontal section taken along the line 5—5 of Figure 3.

As shown in the drawings, a sheet metal office table embodying the invention comprises a table top 2, two hollow end panels or leg members 4 supporting the table top and a drawer 6 and end panel or leg securing means 8, Figures 2 to 5.

The table top 2 comprises a sheet metal plate or top panel 10 which may be covered by linoleum top covering 12 encompassed by a stainless steel trim molding 13 which circumscribes the periphery of the top plate 10 and linoleum top cover 12. The top 2 also comprises a supporting frame work consisting of a pair of longitudi-

2

dinal box panels 14 and 16 having oppositely directed, outwardly turned side flanges 18 spot welded to the top plate at spaced points and an edge frame member 20. The edge frame member 20 comprises a box channel 22 interfitted with a generally L-shaped channel member 24. The box channel 22 is formed with an outer box flange 26 extending perpendicularly to the web of the channel and an inward box flange 28 inclined outwardly and upwardly from the web and terminating in an outwardly directed flange 30 spot welded at spaced points to the inner end portion of the top inwardly directed horizontal flange 32 of the channel 24. It will be apparent that the outer flange 26 of the channel 22 reinforces the web of channel 24 and the channel 22 as a whole reinforces the top supporting flange 32 of the channel 24.

The channel 24 is also formed with an inwardly directed flange 34 underlying the web of the box channel 22 to provide a smooth, rounded lower edge for the table top frame and may be secured to the web of the channel 22 by spot welding at spaced points. It will be evident that the channel 24 extends along the four sides of the table top and provides the usual table skirt.

Each of the hollow end panels or leg members 4 preferably comprises a pair of sheet metal plates or panels 36 and 38 having opposite inwardly offset end portions 40 and 42 fitting into the generally U-shaped end closures 44 formed of sheet metal and secured to the plates 36 and 38 by suitably spot welding to the inwardly offset end portions 40 and 42 of the plates. The plates 36 and 38 may be formed at their lower opposite edges with in-turned flanges such as 46 and 48 terminating just short of the offset end portions 40 and 42 and jointed centrally by one or more splice plates 50 spot welded to the in-turned flanges. Also as shown in Figure 1, plates 36 and 38 may be similarly formed at their top opposite edges with similar in-turned flanges 47 and 49 likewise secured together centrally by one or more of the splice plates 50 spot welded thereto. The end panels also include adjustable feet comprising buttons 52 secured to externally threaded pins 54 received in internally threaded flanged nuts or bushings 56 spot welded to mounting plates 58 having downwardly turned flanges in turn spot welded to the side of the end closures 44.

The drawer 6 is a sheet metal drawer of the usual type and it is slidably mounted on a pair of opposed drawer guides 59 which are supported by spot welding them, respectively, to one of a pair of L-shaped cross rails 61 which are supported by spot welds on the box channels 14 and 16 and extend between a rear rail 60 and front rails 62 and 64. The rails 60, 62 and 64 may be secured in any convenient manner to the web of the box channel 22 at the rear and front of the table top, the rail 60 extending between the end panels 4 and having inwardly turned flanges such as 66 at opposite ends thereof to abut the inner faces of the end panels. The rails 62 and 64 extend between the drawer and an adjacent end panel and are formed with flanges, such as 68, at their outer ends to abut the end panels 4.

The end panels are each secured relative to the table top and rigidified by a pair of panel securing means 8 positioned to telescope with the end closures 44. Each panel securing means comprises a single piece of sheet metal slit and bent to form an upwardly inclined mounting flange 70 spot welded to the upwardly and inwardly inclined flange 28 of the box channel 22 and a main body portion 72 of a width equal to the internal width of the end panels so as to form a close telescoping frictional fit with the end panels. The panel securing means is also formed with inwardly directed parallel side flanges 74 and 76 perpendicular to the main body portion 72, the lower ends of the flanges 74 and 76 being curved inwardly as at 78 and 80 to form camming and guiding surfaces for the

end panels facilitating the ready telescoping of the end panels with the panel securing means. The main body portion 72 is also formed with an inwardly curved lower edge portion 82 forming also a panel camming or guiding surface facilitating the telescoping of the panel with the panel securing means and aligning the panel properly with respect to the front and rear edges of the table top. It may be noted that the sheet metal of the panel securing means is formed with cut-outs 84 to permit the proper inward curving of the lower edge portions 78, 80 and 82 from the side flanges and main body of the panel securing means or bracket.

The opposed sides 74 and 76 of the securing means 8, the opposite sides of the closures 44 and the panel abutting flanges 66 and 68 of the front and rear rails are provided with punched square openings 86 which receive carriage bolts 88, one at each upper corner of the two end panels, the square shank portion of each carriage bolt fitting, non-rotatably, in the square openings in the outer faces of the closures 44 and the flanges 74 of the panel securing means 8. Wing nuts 90, and suitable washers 92, on the inner ends of the bolts clamp against the inturned flanges 66 and 68 of the front and rear rails 60, 62 and 64 so as to detachably secure each end panel 4 to a pair of the panel securing means 8. Panel securing means 8 are of sufficient length on the order of one-quarter the height of the end panels, to substantially increase the rigidity of the end panels against lateral flexibility and inward distortion thereby serving not only to provide a more rigid table supporting structure but also to prevent distortion or bending of the end panels assuring ease of disassembly and subsequent re-assembly.

It will be evident that the table may be shipped in knocked-down form and readily assembled without use of tools of any kind by inverting the table top with the panel securing means 8 projecting upwardly and thereafter the end panels in inverted position easily and readily slide and telescope over or onto the panel securing brackets 8 which brackets automatically locate the panels in proper position perpendicular to the front and rear edges or rails of the table top and precisely located relative to the ends of the table top and is proper abutting relation to the inturned flanges of the front and rear rails 60, 62 and 64. Thereafter by the simple insertion of four bolts 88 through the aligned square openings 86 and the placing of the washers 92 and the placing of the wing nuts 90 on the four bolts 88, the end panels are rigidly but detachably interlocked with the table top. It should also be noted that the camming ends 78, 80 and 82 of the panel securing brackets facilitate this telescoping of the end panels with the brackets and insure a close, tight, frictional fit between the panels and the brackets. Dimensional tolerances in the width of the end panels are compensated by the camming action of the brackets.

It is apparent that widely different embodiments of this invention may be made without departing from the spirit and scope thereof, and, therefore, it is not intended to be limited except as indicated in the appended claims.

I claim:

1. A sheet metal table including a table top comprising oppositely facing interfitted channels forming a peripheral frame, a top panel secured to said frame, hollow sheet metal end panels, a plurality of one-piece brackets each having a top plate secured to said peripheral frame and a depending body portion having laterally directed, parallel end flanges, the external dimensions of the bracket across said flanges being substantially equal to the internal dimensions of said hollow end panels, and said brackets being telescoped into said end panels with the flanges of the brackets contacting the inner wall surfaces of said panels, and detachable means securing said brackets to said end panels.

2. A knock-down sheet metal table comprising a sheet metal table top having a plurality of spaced reinforcing box channels, hollow sheet metal end panels and a plural-

ity of brackets for securing said end panels to said table top, said brackets being secured to certain of said box channels and having spaced flanges for telescoping into said hollow end panels in wall reinforcing engagement with the inner surfaces of said end panels, said brackets and said end panels having aligned openings therein, bolts for insertion in said openings, and wing nuts for securing said bolts when inserted in said openings whereby detachably to secure said panels to said panel locating and rigidifying brackets.

3. A sheet metal table comprising a table top having sheet metal brackets secured to the under surface thereof and depending therefrom, said brackets each comprising a one-piece sheet metal member having a main body portion and spaced parallel flanges extending perpendicular to the main body portion, said flanges at said lower ends having inwardly curved camming tongues, and hollow end panels for telescopically interfitting with said brackets by sliding over said brackets when said camming tongues are inserted in said end panels and the end panels moved or slid toward the table top.

4. A sheet metal table comprising a sheet metal table top having front and rear rails depending therefrom, said rails having at their outer ends inturned apertured flanges, hollow leg panels each comprising a pair of sheet metal plates, closure members secured to and joining the vertical ends of the sheet metal plates and panel securing means comprising one-piece sheet metal brackets each secured at its upper end to the table top and depending therefrom into close fitting telescoping frictional fit with the end panels and positioning the end panels in substantially abutting relation to the inturned flanges of the table top rails, each of said brackets having flanges extending parallel to the sheet metal plates of the end panels and having inwardly turned lower end portions for camming the plates over the flanges upon telescoping of the end panels with the brackets, said panels and said brackets having openings therein aligned with the openings in the inturned flanges of the rails to receive detachable fastening means securing the end panels to the brackets and the rails of the table top.

5. A sheet metal table comprising a reinforced sheet metal table top, a pair of hollow end panels, four sheet metal brackets secured to said table top and depending therefrom, said brackets being arranged in pairs laterally of the table top and the pairs being spaced longitudinally of the table top, each bracket comprising a one-piece sheet metal member having a main body portion extending in the direction longitudinally of the table top and inwardly turned, parallel flanges extending laterally of the table top, the main body portion of each of said brackets and the opposed flanges of each of said brackets having inwardly curved tongues at their lower ends for facilitating telescopic assembly of said end panels with said brackets, said panels adjacent their top edge and their vertical edges having openings therein and said brackets having openings therein in the opposite flanges thereof and aligned with the openings in the end panels for receiving four bolts for attaching the end panels to the table top.

6. A sheet metal table comprising a table top having a channel member forming a peripheral frame, hollow leg panels, each comprising opposed side plates and opposed end closures connecting the side plates, and leg locating and securing means comprising leg securing brackets fixed to the channel member and having generally U-shaped channels projecting from the table top into close fitting telescopic engagement with the inner surfaces of said leg panels, and detachable means for fastening said hollow leg panels to the U-shaped channels of said leg securing brackets.

7. A sheet metal table comprising a table top having a channel member forming a peripheral frame, a pair of hollow end panels each comprising spaced side plates and spaced end closures connecting said side plates, angle

members fixed to the channel member and projecting therefrom into close fitting telescopic engagement with the inner surfaces of said end closures of said end panels for positioning and rigidifying the hollow end panels, and detachable means for fastening said hollow end panels to 5 said angle members adjacent the table top.
